UNITED STATES PATENT OFFICE

ALEXANDER McDONALD, OF PITTSBURGH, AND WILLIAM O. SMITH, OF WILKINSBURG, PENNSYLVANIA, ASSIGNEES OF THIRTY PER CENT TO SAID SMITH AND SEVENTY PER CENT TO JOHN C. YOUNG, OF PITTSBURGH, PENNSYLVANIA

CHIMNEY VENTILATOR

Application filed December 8, 1927. Serial No. 238,540.

The invention relates to chimney ventilators.

The object of the present invention is to improve the construction of chimney ventilators and to provide a simple, practical and efficient chimney ventilator of strong, durable and comparatively inexpensive construction provided with means for producing an upwardly directed current of air about its upper end and to create a strong draft within the chimney.

It is also an object of the invention to provide a chimney ventilator of this character in which the means for causing an upwardly directed current of air will constrict the same as it passes upwardly and inwardly into the ventilator and thereby increase the velocity of the current of air and the effectiveness of the same in creating an up-draft within the chimney.

A further object of the invention is to provide a chimney ventilator of the character stated which shall be adapted to be readily adjusted in a manner to permit of its being used in connection with a chimney of any size.

With these and other objects in view, the invention consists in the construction and novel combination and arrangements of parts hereinafter fully described, illustrated in the accompanying drawings and set forth in the claims hereto appended, it being understood that changes in the form, size and minor details of construction, within the scope of the claims, may be resorted to without departing from the spirit of the invention or sacrificing any of the advantages thereof.

In the drawings:

Figure 1 is a view in side elevation of the chimney ventilator.

Fig. 2 is a top plan view of the chimney ventilator.

Fig. 3 is a sectional view taken on a plane extending vertically and centrally through the chimney ventilator.

Fig. 4 is a perspective view of two of the sections of the chimney ventilator.

Fig. 5 is a sectional view of one side of the

chimney ventilator, section being taken on the line 5—5 of Fig. 3.

Fig. 6 is a sectional view taken on the plane indicated by the line 6—6 of Fig. 2.

Fig. 7 is a detail perspective view of one of the vane holding clamps.

Fig. 8 is a detail view of one of the central partitions.

Fig. 9 is an enlarged detail vertical sectional view on the line 9—9 of Fig. 5.

Fig. 10 is a perspective view of the section of the chimney ventilator which slidably interlocks with the right-hand section shown in Fig. 4.

In the accompanying drawings, in which is illustrated the preferred embodiment of the invention, the chimney ventilator comprises a main pipe 1, the lower end portion of which is adapted to have a snug fit in the chimney, an auxiliary pipe 2 which is shorter than the main pipe and arranged in spaced relation to and about the upper end thereof, and lower and upper air deflecting frustums 3 and 4, respectively, which are located below the auxiliary pipe and adapted to direct air entering between them to and through the space 5 between the main and auxiliary pipes. The air passes directly upward from the space 5 and creates a strong updraft within the chimney.

The main pipe 1 is rectangular in plan. It is of sectional formation, and each of the four sections thereof consists of right angularly related and vertically disposed plates 6 and 7. The plates 6 and 7 of certain of the sections are provided at their upper and lower edges with inturned flanges 8 which slidably receive the upper and lower edges of the remaining sections, so as to slidably and adjustably connect the sections together in a manner to permit the sections to slide inward and outward to enable the horizontal dimensions of the main pipe 1 to be varied. Certain of the plates of the sections are provided with horizontally arranged slots 9, to receive the uncut portions of the cooperating sections so as not to interfere with the said inward and outward horizontal sliding movement of the sections to vary the size of the chimney ventilator.

The auxiliary pipe 2 is also rectangular in plan and of sectional formation. Each of its four sections consist of vertically disposed and angularly related plates 10 and 11. The upper edges of certain of these sections are provided with inturned flanges 12 which slidably receive the corresponding edges of the remaining sections, so as to adjustably connect the sections in a manner to permit the horizontal dimensions of the auxiliary pipe 2 to be varied.

The lower frustum 3 is of sectional formation, and each of the four sections thereof consist of right angularly related plates 13 and 14. These sections are provided at their inner or upper edges with upstanding flanges 15 and at their outer or lower edges with inturned flanges 16. The respective sections of this frustum are secured to the respective sections of the main pipe 1 through the medium of the flanges 15. The flanges 16 of certain of these frustum sections fit in the corresponding flanges of the remaining frustum sections, so as to permit these sections to be adjusted relatively while the horizontal dimensions of the main pipe 1 are being varied. Portions of the inner or upper edges of certain of the plates 13 and 14, are cut away or recessed beyond the attaching portions or flanges 15, as clearly illustrated in Figs. 3, 9 and 10 of the drawings, and are thereby spaced from certain of the plates 6 and 7 of the main pipe sections, so as to provide clearance spaces or slots 17, which, together with the slots 9, receive the inner portions of the remaining plates 13 and 14. As the frustum sections are slidably associated, and as the respective frustum sections are fixed to the respective main pipe sections, the horizontal dimensions of the frustum will be varied as the corresponding dimensions of the main pipe sections are varied. The interfitting slotted portions of the sections of the main pipe and the sections of the lower frustum interlock the said sections against lateral separation.

The upper frustum 4 is similar to the lower frustum 3, and the plates 18 and 19 of the respective sections thereof are arranged at right angles and provided at their lower or outer edges with inturned flanges 21. The inner or upper edges of the respective sections of this frustum are connected to the lower edges of the respective sections of the auxiliary pipe 2. The flanges 21 of the respective sections are slidably associated, so as to permit the horizontal dimensions of this frustum to be varied as the corresponding dimensions of the main pipe 1 are varied.

The respective sections of the auxiliary pipe 2 and frustum 4 are secured to and supported from the respective sections of the lower frustum 3 by diagonally disposed plates 22 which are secured to and between

the frustum sections at the corners thereof. The plates 22 are arranged in pairs and the members of each pair are fitted flat against each other and secured together by rivets 22^a or other suitable fastening means to provide spacing and supporting elements of two plies or thicknesses. The pairs of plates are provided at their upper and lower edges with laterally extending flanges 22^b and 22^c, which are riveted or otherwise secured to the upper and lower tapered members or frustums. The plates 22 form partitions and divide the space between the upper and lower frustums 3 and 4 into a plurality of inwardly and upwardly tapering compartments which communicate at their lower or outer ends with the atmosphere and at their inner or upper ends with the space 5 and their inward taper tends to increase the velocity of the air currents and render the same more effective in creating an upward draft within the chimney.

Vanes 23 are secured to the upper faces of the upper frustum 4 and to the outer faces of the sides of the auxiliary pipe 2 by U-shaped clamps 24. The vanes have angularly related upper and lower portions, the upper portion being vertical and the lower portion inclined. Each vane is constructed of a single piece of sheet metal folded longitudinally to provide a body portion of two plies or thicknesses. The side edges of the sheet metal are bent outwardly to form laterally extending flanges 26. In the manufacture of the vanes a portion of the body of the vane is removed and the flange is bent transversely to form the angularly related portions and the adjacent ends of the severed portions of the body are secured together by soldering or other suitable means. The angularly related upper and lower portions of the vanes may, however, be formed in any desired manner, as will be readily understood.

The clamps 24 saddle the upper edges of the auxiliary pipe 2 and the outer sides of the U-shaped clamps are bifurcated or slotted at 24^a to permit the clamps to straddle the body portion of the vanes and engage the laterally extending flanges at opposite sides of the said body portion. The clamps 24 are secured in place by set screws 25 which also serve to secure the sections of the ventilator in adjusted position. The vanes 23 are positioned centrally of the sides of the frustum 4 and they extend from the upper edge of the auxiliary pipe 2 to the lower edge of the frustum. The flanges 26 are located at the inner edges of the vanes 23 and fit against the auxiliary pipe 2 and the frustum 4 and both flanges are engaged by the bifurcated outer side of the clamps.

From the foregoing description, taken in connection with the accompanying drawings, it should be apparent that the ventilator

may readily be adjusted so as to adapt it for use in connection with a chimney of any size. The lower end portion of the main pipe 1 fits in the chimney and the lower edge of the lower frustum 3 rests upon the chimney. The air entering the compartments formed by the frustums 3 and 4 and the plates 22 passes upwardly through the space 5 between the main pipe 1 and auxiliary pipe 2. The air passes upwardly from the space 5 and creates a strong updraft in the chimney. The air impinging against the upper side of the frustum 3 is caused to travel upwardly between the main pipe 1 and auxiliary pipe 2 due to the inclination of the frustum, and this current of air assists in creating a strong updraft in the chimney. The air currents striking the outer surfaces of the frustum take a similar course, which adds to the upward pull on the contents of the chimney.

The upward current of air may be further strengthened, especially when the wind is striking the corners of the chimney ventilator, by means of centrally arranged partitions 27 disposed in vertical planes and conforming to the shape of the space between the upper and lower frustums or hollow members and extending to the main tube. The central partitions 27 are each constructed of a single piece of sheet metal folded longitudinally to form a body portion of two plies or thicknesses and having its side edges bent outwardly at right angles to form laterally extending flanges 28 which are located at the lower edge of the central partition. The inner end of the centrally arranged partition is tapered as shown to arrange the inner end edge in a vertical position to fit against the main pipe. The outer end edge of the central partition is arranged perpendicular to the outer edge, which is disposed at an inclination. This square construction of the outer end of the central partition will cause the upper outer corners 29 of the central partition to project beyond the upper frustum. By projecting the upper outer corners 29 of the central partition beyond the other parts of the apparatus, the central partitions are adapted to catch and direct more air into the divided spaces or compartments, than would be the case were the outer edges of the central partition arranged in vertical planes similar to the outer end edges of the diagonally disposed plates 22. The central partitions, which also brace and increase the strength and rigidity of the projecting portions of the chimney proper, are secured in position by bottom clamps 30 constructed in the same manner as the clamps 24 heretofore described, and engaging the laterally extending flanges of the central partitions and the lower frustum of the chimney ventilator. One clamp at the bottom of the central par-

titions will be sufficient to secure the same firmly in position between the upper and lower frustums.

It should be understood that the drawings are merely illustrative and do not pretend to give exact proportions. Furthermore, the said drawings are illustrative of a preferred construction, it being our expectation that various changes and modifications may be made without departing from the spirit and scope of our invention.

What is claimed is:

1. A chimney ventilator comprising a main pipe consisting of angular sections, means slidably connecting the sections, a lower frustum consisting of angular sections and secured to the sections of the main pipe, an upper frustum consisting of angular sections and secured to the sections of the lower frustum, and an auxiliary pipe consisting of angular sections secured to the sections of the upper frustum and spaced from the main pipe, the sections of the lower frustum and the main pipe having interfitting slotted portions interlocking such sections against lateral separation.

2. A chimney ventilator comprising a main pipe consisting of angular sections, means slidably connecting the sections, a lower frustum consisting of angular sections and secured to the sections of the main pipe, an upper frustum consisting of angular sections and secured to the sections of the lower frustum, an auxiliary pipe consisting of angular sections secured to the sections of the upper frustum and spaced from the main pipe, and means for securing the sections against casual relative movement, the sections of the lower frustum and the main pipe having interfitting slotted portions interlocking such sections against lateral separation.

3. A chimney ventilator comprising relatively adjustable sections, vanes, and fastening means securing the vanes in place, said fastening means also holding the sections against relative movement.

4. A chimney ventilator comprising a main pipe, an auxiliary pipe arranged in spaced relation to the main pipe, upper and lower deflecting frustums carried by the said pipes and arranged in spaced relation, the space between them communicating with the space between the said pipes, and diagonally disposed partitions for dividing the space between the frustums into inwardly and upwardly tapered compartments for increasing the velocity of the air currents passing upwardly through the space between the said pipes, said partitions consisting of plates arranged in pairs and secured together to form spacing and supporting elements and having their upper and lower edges bent laterally to form attaching flanges.

5. A chimney ventilator comprising a

frustum provided with an upper vertical portion, vanes having angularly related upper and lower portions and provided with laterally extending flanges fitted against the said upper and lower portions of the said frustum, and substantially U-shaped clamps saddling the frustum and the flanges and securing the vanes to the frustum.

6. A chimney ventilator comprising a frustum provided with an upper vertical portion, vanes having angularly related upper and lower portions and provided with laterally extending flanges fitted against the said upper and lower portions of the said frustum, and approximately U-shaped clamps saddling the frustum and provided with bifurcated upper portions straddling the vanes and engaging the laterally extending flanges.

7. A chimney ventilator including a frustum having a vertical upper portion, vanes having angularly related upper and lower portions and each consisting of a piece of sheet metal folded longitudinally to provide a body portion of two plies or thicknesses and having its side edges bent outwardly to form laterally extending flanges, the latter being fitted against the exterior of the frustum, and substantially U-shaped clamps saddling the upper and lower edges of the frustum and having bifurcated upper portions straddling the outer portions of the vanes and engaging the laterally extending flanges.

8. A chimney ventilator comprising a main pipe consisting of angularly related sections, certain of the sections being provided at their upper and lower edges with inturned flanges forming ways slidably receiving the upper and lower edges of the adjacent sections, a lower frustum consisting of angular sections secured to the sections of the main pipe and having inwardly bent lower edges slidable on each other, the sections of said lower frustum being secured to the sections of the main pipe and certain sections of the main pipe and the lower frustum being provided with horizontally disposed cut away portions to permit the sliding of the adjacent sections, an upper frustum provided with a vertical upper portion forming an auxiliary pipe, said upper frustum and auxiliary pipe consisting of angular sections, certain of the sections being provided with inwardly extending flanges forming ways slidably receiving the adjacent sections, and means for supporting the upper frustum and the auxiliary pipe in spaced relation with the lower frustum and the main pipe.

9. A chimney ventilator comprising a main pipe consisting of angularly related sections, certain of the sections being provided at their upper and lower edges with inturned flanges forming ways slidably re-

ceiving the upper and lower edges of the adjacent sections, a lower frustum consisting of angular sections secured to the sections of the main pipe and having inwardly bent lower edges slidable on each other, the sections of said lower frustum being secured to the sections of the main pipe and certain sections of the main pipe and the lower frustum being provided with horizontally disposed cut away portions to permit the sliding of the adjacent sections, an upper frustum provided with a vertical upper portion forming an auxiliary pipe, said upper frustum and auxiliary pipe consisting of angular sections, certain of the sections being provided with inwardly extending flanges forming ways slidably receiving the adjacent sections, and diagonally disposed partitions interposed between the upper and lower frustums and secured to the same and supporting the upper frustum and the auxiliary pipe in spaced relation with the lower frustum and the main pipe.

10. A chimney ventilator comprising a main pipe, an auxiliary pipe spaced from the main pipe to provide an intervening passage, upper and lower frustums arranged in spaced relation exteriorly of the main pipe, the upper frustum being spaced from the main pipe to form a passage, connecting with the lower end of the said passage between the main and auxiliary pipes exteriorly arranged vanes extending across the upper faces of the upper frustum and having laterally extending flanges fitted against the same, vertically disposed partitions conforming to the shape of the space between the frustums and located in the same vertical planes as the vanes and having laterally extending flanges fitting against the upper faces of the lower frustum, and fastening means for securing the laterally extending flanges of the vanes and the partitions to the frustums.

11. A chimney ventilator comprising a main pipe, upper and lower frustums arranged in spaced relation exteriorly of the main pipe, the upper frustum being spaced from the main pipe to form a passage, exteriorly arranged vanes, vertical partitions conforming to the shape of the space between the frustums and having tapered inner ends to fit the main pipe and provided with substantially square outer ends forming projecting portions extending beyond the frustums for directing the air in the spaces between the latter.

In testimony whereof, we have hereunto affixed our signatures at Pittsburgh, in the county of Allegheny and State of Pennsylvania, this 23rd day of November, 1927.

ALEXANDER McDONALD.
WILLIAM O. SMITH.
